ROAD JOINT MACHINE

John N. Heltzel, Warren, Ohio

Application March 8, 1930, Serial No. 434,290

12 Claims. (Cl. 94—45)

The present invention relates to improvements in road joint machines and more particularly refers to a machine operable to form a groove or trough longitudinally in the plastic concrete 5 of the roadway for the purpose of forming a joint and to receive a joint strip or joint material if desired.

An object of the invention is to provide an improved road joint machine designed to be manipulated or propelled by hand operation at 10 the side of the roadway to the end that the freshly laid concrete will not be interfered with and will not form an obstruction to the proper operation of the machine.

Another object of the invention is to provide 15 an improved road joint machine which may be trailed behind a finishing machine or other vehicle by the use of cables or appropriate device.

A further object of the invention is to provide 20 an improved road joint machine in which provision is made for the adjustment of the device to different widths of roadway, and in which provision is also made for the support of the cutter in an operative or an inoperative position.

With the foregoing and other objects in view, 25 the invention will be described more fully hereinafter and more particularly pointed out in the appended claims.

In the drawings in which like reference characters refer to like or corresponding parts 30 throughout the several views.

Figure 1 is a top plan view, with parts broken away and parts shown in section, of one form 35 of improved road joint machine constructed in accordance with the present invention.

Fig. 2 is a vertical sectional view taken on the line 2—2 in Fig. 1.

Fig. 3 is a similar view taken on the line 3—3 also in Fig. 1.

Fig. 4 is a perspective view of a preferred embodiment of the invention.

Fig. 5 shows the inverted position of the device illustrated in Fig. 4 with the shaft shown in section.

Fig. 6 is a top plan view showing a further modified form of machine.

Fig. 7 is a longitudinal central sectional view taken on the line 7—7 in Fig. 6 and

Fig. 8 is a cross section taken on the line 8—8 also in Fig. 6.

It will probably be convenient to refer first to Figures 4 and 5 on account of the simplified showing and my preference for this embodiment of the invention.

At the outset, it will be understood that an

ordinary finishing machine is used to screed off the concrete after it has been deposited in the subgrade by the transit mixers or trucks. The finishing machine will be equipped with the usual screed member operating on the side forms which are indicated at 10 and between which the concrete is laid. Trailing immediately in the rear of the finishing machine is a joint cutting blade 11. I have illustrated this blade as a disk or circular cutter mounted on a shaft 12 which extends transversely of the roadway and possesses sufficient length to extend beyond both of the side forms 10. The projecting end portions of the shaft 12 are coupled to cables 13 carrying hooks 14 which may be detachably connected with the finishing machine. In this way the shaft 12 will be trailed after the finishing machine, the blade 11 resting in the plastic concrete and forming a groove or trough 15 as the machine proceeds. It will be understood that the finishing machine proceeds ahead and acts to screed down the concrete when it is required that the finishing machine screed the surface as usually is the case.

The cables 13 may be connected to the shaft 12 in any appropriate manner; as by being secured in the eyes 16 carried by the sleeves 17 which are freely mounted on the shaft 12 and confined at both ends by the thrust collars 18, such collars being fixed to the shaft 12 in any appropriate manner. The blade 11 is free to rotate on the shaft 12 and is supported against lateral movement by collars 19 at each side thereof. The collars 19 are secured to the shaft as by the use of set screws 20 which will permit the collars and incidentally the disk 11 to be shifted laterally along the shaft 12 to a desired position.

The shaft 12 is supported at its opposite end portions in sleeves 21, and the sleeves are carried by rollers or wheels 22 which run upon the side form 10. The wheels 22 are preferably provided with flanges at each side of the form 10 in order to preserve the alignment of the machine.

The sleeves 21 are held to the shaft by the use of set screws 23 or the like. By loosening the set screws, the sleeves 21 may be adjusted axially along the shaft 12 whereby to change the gage between the two wheels 22 and therefore provide for various widths of road. Solid link may be used instead of cable 13—making a rigid connection to the finishing machine or other vehicle—

permitting the apparatus to be reciprocated back and forth longitudinally of the roadway.

Handles 24 are carried on the sleeves 21 at opposite sides of each of the wheels 22 and in the

normal operative position extend forwardly and downwardly whereby the flanged rollers 25 carried by the forward portions of the arms 24 may engage and roll upon the forms 10 in advance of the wheels 22. The sleeves 21 also carry upstanding pairs of arms 26 at opposite sides of the wheels 22 for the purpose of supporting flanged rollers 27 which may also engage the side forms 10 when the device is inverted as shown in Fig. 5.

In the use of this form of the invention, Fig. 4 shows the operative position of the parts, with the disk or cutting blade engaging in the plastic concrete and forming the groove 15. The wheels 22 and flanged rollers 25 engage on the side forms 10 in the act of advancing the blade 11 through the concrete. This advancing movement may be imparted to the machine through the cables 13 from the finishing machine, or the hooks 14 may be disconnected from the finishing machine and the device may be operated by hand, resort for this purpose being had to the handles 24. In such case the operators will reciprocate the device longitudinally on the side form, two operators being employed for this purpose, one at each side of the roadway.

Fig. 5 shows the disk cutter 11 released from the concrete, which is accomplished by reversing the handles 24, bringing both rollers 25 and 27 in contact with the side forms 10. In this position the joint cutting apparatus may be suspended above the surface of the roadway and transported on the side forms by the rollers 25 and 27.

Referring now more particularly to Figs. 1, 2 and 3, a cutting disk 11a is shown as carried by a spindle 28 supported in the forward end of arms 29 having collars 30 affixed, as by set screws 31, to a shaft 32. This shaft 32 extends transversely of the roadway and on the sides of the forms 33. To the projecting ends of the shaft 32 may be coupled cables 34 having hooks 35 by which it may be trailed after a finishing machine. Sleeves 36 telescope the opposite end portions of the shaft 32, such sleeves 36 being affixed to the shaft 32 as by means of set screws 37. At their outer ends the sleeves 36 are journaled in the trucks 38, and the trucks are supported upon the flanged wheel 39 adapted to travel upon the side forms 33. Levers 40 are fixed at the outer ends of the sleeves 36 of the trucks 38, and carry latches 41 for cooperating with two toothed segments 42 whereby to hold the levers 40 in adjusted angular position.

By shifting the levers 40, a partial rotary movement may be communicated to the sleeves 36 and to the shaft 32 for the purpose of raising and lowering the cutting disk 11a. In this way the disk 11a may be lowered to an operative position in contact with the plastic concrete or it may be raised up to an inoperative position clear of the concrete. By use of the levers 40, a chopping action of the disk in the concrete may also be effected. Such procedure will be desirable when the concrete becomes too hard. By loosening the set screws 37, the sleeve 36 may be adjusted axially along the shaft 32 for the purpose of widening or narrowing the gage between the trucks to accommodate different widths of roadway. Freely rotatable upon the sleeves 36 are tubular shafts 43 having longitudinal grooves 44 therein to receive the keys 45 carried within collars 46 which are slidable axially along the tubular shafts 43. The outer ends of yoke arms 47 are connected to the collars 46. Centrally of the machine, the yoke arms 47 are joined to a

support 48 for a grooving tool 49. The support 48 at its forward end is coupled to a collar 50 freely rotatable on the shafts 32 between the collars 30 for the grooving tool or disk 11a. The outer ends of the tubular shaft 43, which terminate inside of the truck 38, are affixed to levers 51 which are also provided with latches for cooperating with the toothed quadrants 52. The quadrants are carried by the truck frames 38.

In the operation of this form of the machine, it will be understood that the grooving tool 11a will move in advance of the grooving tool 49. It will furthermore be understood that the disk cutter 11a may be used without the grooving tool; or likewise the grooving tool 49 may be employed without the disk cutter 11a. The grooving tool is manipulated in and out of the concrete by the levers 51 operating through the tubular shafts 43 upon the yoke arms 47 and the support 48. The grooving tool 49 may also be manipulated up and down, producing a chopping action in the concrete, particularly where the concrete becomes too hard.

After the groove in the concrete has been prepared, it is desirable in some cases to install joint strips, which may either remain permanently in the concrete or may be removed later and the joint filled with suitable filler. To accomplish this, I provide the device shown in Figs. 6, 7 and 8.

Referring more particularly to Figs. 6, 7 and 8, I provide a traveling bridge consisting preferably of transverse I beams connected by longitudinal sills 54 and 55. The sills 54 and 55 carry between them the grooved or flanged wheels 56 for operating upon the side forms 57.

A workman's platform 58 is carried in the transverse I beams 53, and, as shown in Fig. 8, a reinforcing member 59 projects down from the bottom of the platform into the plastic concrete to serve as a guide for the purpose of guiding and aligning the joint strip indicated at 60. The platform is arranged for vertical adjustment up and down whereby the reinforcing member 59 may be moved in and out of the concrete. This action may be secured by the use of adjusting screws 61 rotatably attached at their lower ends to the platform 58 and having threaded engagement with the upper portions of housings or yokes 62. Guides 63 carried by the platform 58 are slidable vertically in guideways provided in the sides of the housings or yokes 62. The housings or yokes 62 are supported by rollers 64 which engage in the troughs of the I beams as indicated in Fig. 7.

Hand wheels 65 may be provided upon the upper ends of the adjusting screws 61 above the housings or yokes 62 for convenience in adjustment of the platform and reinforcing member. It will be appreciated that the platform 58 and the reinforcing member 59 constitute a unitary combination economically constructed to install and align the joint.

By reason of the rollers 64 being movable in the I beams 63, the platform 58 is permitted a transverse adjustment across the roadway in order to bring the reinforcing member 59 to a correct position with regard to the joint groove, prepared by the disc cutter, moving over the roadway by the finishing machine. Spacing members or shafts 66 are freely slidable in bearings 67 carried by the inner longitudinal sill 55 at one side of the machine. Coupled between the inner ends of the spacing members 67 and the platform 58 are turnbuckles 68 or other appropriate adjusting

means whereby the length of the spacing members may be adjusted.

The outer ends of the spacing members 66 carry flanged rollers 69 which rotate on spacing member 66 but rollers 69 do not shift laterally on the members 66, and rollers 69 travel upon the side form 57. Now it will be understood that the supporting rollers or wheels 56 for the traveling bridge or carriage are rotatably supported upon elongated shafts 70 mounted between the sills 54 and 55. These wheels 56 have a free movement over the longitudinal shafts 70 so that the traveling bridge or carriage may have a free and unrestricted lateral movement, or in other words the wheels 56 may be slid in and out on the shafts 70 to accommodate roadways of various widths and to enable the wheels 56 to engage the upper tread surfaces of the side forms 57 which may be situated at various distances apart.

The turnbuckle 68 may be manipulated to either lengthen or shorten the adjusting members or shafts 66. This adjusting movement of the turnbuckle 68 is also necessary in order to bring the platform 58 to a correct central position whereby the reinforcing member 59 may engage in the joint groove of the concrete roadway produced by a cutter disc in advance as described. Produced by a cutter in advance of this machine as is sometimes the general practice. However, this apparatus may be used for installing joints in plastic concrete without preparing a groove in advance, provided the material is of the proper consistency.

The shafts 66 thus have free longitudinal movement through the bearings 67 so as to permit the carriage, which is supported upon the wheels 56, to be unrestricted as to lateral movement. At the same time, the platform 58 may remain in a fixed spaced position, it being noted that when the main carriage shifts laterally of the roadway, the rollers 64 will rotate in the I beams 53 and therefore there will be no restriction to the lateral movement of the beams 53 of the carriage. Therefore, the wheels 56 of the main carriage do not act as spacers and may have more or less free lateral movement, which will not affect gaging of the platform 58 to which the joint aligning blade 59 is attached.

The carriage may be provided with a hand propelling wheel 71 having bearings 72 in the sills 54 and 55. The shaft of the hand wheel 71, which shaft is indicated at 74, is provided with a sprocket 73, shown in Fig. 7. This sprocket 73 engages a chain 75 which further extends about the sprockets 76 on the shaft 70 of the wheel 56 at one side of the machine.

In the use of this form of the invention, the traveling carriage is propelled along the side forms by rotating the hand wheel 71. The carriage may be laterally adjusted as indicated, and the platform 58 may also be shifted laterally in the I beams 53, the adjustment being had through the turnbuckles 68.

In this way the reinforcing member 59 is brought to correct alignment with the groove in the concrete roadway in which it is desired to insert the joint strip 60. The reinforcing strip 59 will act as a guide for the strip 60 and will admit of the same being correctly and quickly placed.

If desired, the machine may be trailed by a finishing machine well-known in the art—that is, it may be trailed continuously or alternately as may be desired.

If desired, the machine may be trailed intermittently rearwardly of a finishing machine.

Having thus described the invention, what is claimed as new is:

1. An improved road joint machine comprising a cutting tool, a shaft for supporting said tool, wheels adjustable along said shaft and adapted to travel the side forms of the roadway, and means connected to said shaft whereby the tool may be drawn along trailing a finishing machine. 80

2. An improved road joint machine comprising a cutting tool, a shaft for the cutting tool, wheels connected to said shaft for traveling upon the side forms of the roadway with the cutting tool engaging in the concrete, and means whereby the shaft may be supported for rolling movement along the forms with the cutting tool out of the concrete. 85

3. An improved road joint machine comprising a cutting tool, a shaft therefor, flanged wheels axially adjustable along said shaft and for traveling along the tread surfaces of the side forms of the roadway, and rollers associated with said wheels and adapted to engage 100 the forms for holding the cutting tool out of contact with the concrete. 95

4. An improved road joint machine comprising a cutting tool, a shaft for the cutting tool, means supporting said shaft and adapted to 105 move along the side forms of the roadway, rollers also adapted to engage the side forms of the roadway for holding the wheels suspended and the cutter out of contact with the concrete, and means associated with said rollers for permitting of the hand manipulation of the tool. 110

5. An improved road joint machine comprising a cutting tool, a shaft for the cutting tool, means whereby the cutting tool may be adjusted along the shaft, supports for the shaft 115 adapted to move along the side forms of the roadway with the cutting tool in operative contact with the concrete, and other normally inactive supports for the shaft adapted to hold the cutting tool out of contact with the concrete. 120

6. An improved road joint machine comprising a shaft extending transversely of the roadway, means for supporting said shaft for rolling movement longitudinally of the roadway, 125 a cutting tool supported by said shaft, means for rotating the shaft to raise and lower the cutting tool, a grooving tool also carried loosely by said shaft, and means for raising and lowering said grooving tool. 130

7. An improved road joint machine comprising a shaft extending transversely of the roadway, trucks for supporting said shaft for rolling movement upon the side forms of the roadway, the ends of the shaft extending beyond 135 said trucks, connections to the extending ends of the shaft whereby the machine may be drawn along trailing a finishing machine, a cutting tool fixedly carried by said shaft, and means for oscillating said shaft to raise and lower the cutting tool. 140

8. An improved road joint machine comprising a shaft extending transversely of the roadway, trucks carrying said shaft upon the side forms of the roadway, arms affixed to said shaft, 145 a cutting tool carried by said arm, tubular shafts extending about the firstnamed shaft, a grooving tool following said cutting tool, a yoke longitudinally slidable on said tubular shaft but 150

- compelled to rotate with said tubular shafts, and independently adjustable means coupled to said firstnamed shaft and to the tubular shafts for rocking the same to move the cutting and 5 grooving tools into and out of the concrete.
9. A joint cutting apparatus, comprising a transverse member spanning a road under construction, means associated at ends of said member to engage sideforms to support the apparatus for longitudinal movement over the road, a cutting disc associated with the first member substantially in center of the road, to operate in plastic concrete to produce a separation therein, a blade to follow in the cleft to 10 produce a further separation, and means for movement of the apparatus over the roadway.
10. In a device of the character described, a joint cutting blade, a transverse support for 20 the blade, wheels sustaining the support and adapted to roll along the side forms while the blade is in joint cutting engagement with the concrete, and rollers carried by said support in the same plane with and beyond the periphery of said wheels for rolling along the side 25 forms to sustain the blade out of contact with the concrete.
11. In a device of the character described, a joint cutting disc, a transverse shaft along which the disc is adjustable, sleeves adjustably attached to the end portions of the shaft, 80 wheels on the sleeves for rolling on the side-forms with the disc adjusted to penetrate the concrete, handles attached to the sleeves, arms also attached to the sleeves and angularly displaced from the handles, and flanged rollers in the handles and arms adapted to roll along the side forms when the device is inverted with the disc suspended out of contact with the concrete. 85
12. In a device of the character described, joint cutting means, a transverse support for said means, wheels carrying the support with the cutting means penetrating into the concrete when the wheels are placed on the side forms, and carrying devices for supporting the wheels out of contact with the side forms and holding the cutting means out of engagement with the concrete. 90
